UNITED STATES PATENT OFFICE.

FRANCIS J. SCHMIDT, JR., OF WAUWATOSA, WISCONSIN, ASSIGNOR OF ONE-HALF TO
H. J. WAGNER, OF MILWAUKEE, WISCONSIN.

REFRIGERATOR.

1,325,585.

Specification of Letters Patent.

Patented Dec. 23, 1919.

Application filed February 14, 1916. Serial No. 78,172.

To all whom it may concern:

Be it known that I, FRANCIS J. SCHMIDT, Jr., a citizen of the United States, residing at Wauwatosa, county of Milwaukee, and 5 State of Wisconsin, have invented new and useful Improvements in Refrigerators, of which the following is a specification.

My invention relates to improvements in refrigerators.

10 The object of my invention is to provide means for affording access to any one of a series of compartments in a compartment refrigerator without opening the other compartments or permitting the escape of cold 15 air therefrom, or the admission of warm air thereto.

In the drawings—

Figure 1 is a vertical sectional view of a refrigerator embodying my invention.

20 Fig. 2 is a horizontal sectional view, drawn on line $x-x$ of Fig. 1.

Like parts are identified by the same reference characters in both views.

The main or refrigerating chamber proper 25 is provided with double walls 1 and 2, having a double walled door 3, the upper portion of which is provided with panels 4 and 5 composed of glass, whereby the interior may be inspected. A rotating member, sub- 30 divided into a series of compartments, is located within the inclosure formed by the walls 1 and 2 and is adapted to receive the articles stored in the refrigerator. This rotating member comprises a floor 5' and 35 cap 6, supported from the floor by a set of partitions 7, 8 and 9. These partitions may be arranged in any desired manner.

In the construction shown, the partition 7 occupies the central portion of the rotary 40 member and crosses its axis of rotation. The partitions 8 extend across the respective ends of the partition 7 and the partitions 9 project outwardly from the partitions 8, parallel with the plane of the partition 7, 45 projected, but on opposite sides thereof and spaced therefrom. The outer side margins of the partitions 8 and 9 are provided with vertical posts or strips of suitable material 11, the outer surfaces of which are in arcs 50 coinciding with the circle of rotation about the central axis. The bottom and top walls 5 and 6 respectively, are provided with axial guide trunnions 12 and 13, journaled in bearing members 14 and 15 on the floor and 55 ceiling of the main chamber. The trunnions

12 and 13, however, are employed simply as guides, the rotary member being supported by gear wheels or rollers 20, 21 and 22, which are adapted to engage a circular rack 24 mounted on the lower surface of the 60 floor 5'. The rollers 20, 21 and 22 are journaled in suitable bearing members 26 mounted upon the floor of the main chamber. This arrangement of partitions is also adapted to prevent sagging or yielding of 65 the floor of the revolving chamber, such as would otherwise cause unequal distribution of the load, or interfere with the rotary movements. It will be observed that the central portion of the floor 5', and also of the 70 ceiling 6 is reinforced, and that the central partition 7 crosses this reinforcement centrally, whereas the partitions 8 cross its margins. The reinforced floor co-operates with the partitions to prevent sagging at 75 the center, and the load is therefore uniformly distributed with light pressure upon the central trunnion 12. The structure thus produced rotates easily, and without irregular or jolting movement. 80

The rotary member may be rotatively adjusted to any desired position by means of a manually operated crank wheel 28, the motion of which is transmitted through the crank shaft 29, sprocket chain 30, shaft section 31, gear wheel shaft 32, gear wheel or roller 20, and circular rack 24. The shaft 31 has slip coupling relation at 35 with the roller or gear wheel shaft 32, so that if desired, the crank wheel and its associated 90 parts, to and including shaft section 31, may be mounted on or within the door. When the door is open, the shaft section 31 will slip out of the coupling 35, whereby the portion of the adjusting mechanism carried by 95 the door may be permitted to swing with the door. Therefore, the crank wheel may be conveniently located in a position to enable the operator to inspect the rotary member through the glass panels 4 and 5, while operating the crank to adjust the desired compartment of the refrigerator into registry with the door. 100

Gear wheel or roller 21 may be provided with a projecting shaft 37 which may be 105 connected with any suitable source of power, if the rotary member is too large or heavy to be conveniently operated by hand. The other rollers 22 are idle rollers or gear wheels. It is immaterial whether friction 110

wheels or toothed gear wheels are employed. Where gear wheels are employed, the rack 24 will of course be provided with suitable teeth.

- 5 The door jamb is provided with inwardly projecting walls 40, and packing strips 41 are secured to one side face of each of these walls in a position to project inwardly therefrom into frictional contact with the posts or members 11. A bar 43 is hinged at 44 to the lintel of the door and is also provided with a flexible packing strip 45, which is adapted to rest upon the top 6 of the rotary member, when the door is open. When the door is closed, 10 it engages a projection 46 on bar 43, whereby said bar is tilted, as shown in Fig. 1, thereby raising the packing strip 45 above the top or cap member 6 to avoid friction. The packing strips 41 extend upwardly to a 15 point where their upper ends will be engaged by the packing strip 45 when the latter drops to a horizontal position.

The posts or strips 11 and the respective partition members with which they are associated, are so arranged and spaced apart that any two adjacent posts or strips 11 may be brought into simultaneous registry with both packing strips 41, whereby one compartment, and only one, will be exposed to 20 permit a discharge of cold air or receipt of warm air from the exterior when the door is open. These packing strips 41 also prevent any circulation of air through the door into the spaces surrounding the rotary member. 25 The packing flap 45 prevents air from passing into the space above the packing member. I do not consider it necessary to provide packing for the floor of the refrigerator, since the cold air will have very little 30 tendency to escape, unless warm air is permitted to enter the upper portion of the refrigerator.

The various compartments of the rotary member may, as above stated, be arranged 45 in any convenient manner, except that the outer wall margins must be spaced apart a distance equal to the distance between the packing strips 41, *i. e.*, the width of the door way. The partition walls of the compartments may be provided with hooks 50 or any other suitable supports for the articles which are to be stored.

With the above described construction, 55 the operator will first utilize either the crank wheel or the power shaft to actuate the rotary member or support until the desired compartment is brought in registry with the door. Such condition of registry may be ascertained by watching the revolving member 60 through the glass panel. When the desired compartment is in proper registry with the packing strips engaging the vertical strips or post 11, the revolving member may be brought to rest and the door may then 65 be opened, the packing strip 45 dropping

upon the top or cap of the rotary member, as soon as the door moves out of contact with projection 46. All other portions of the refrigerator, except the compartment which is thus exposed, will remain closed, 70 the closure being practically as complete as if the door were shut. In the construction shown, the main chamber is illustrated as a rectangular chamber which, in connection with the rotary member therein, provides spaces at its corners. This is not essential but I preferably employ a rectangular chamber in order that ice, or other refrigerant, may be conveniently stored in the corners in most effective relation to the rotary member. To avoid providing additional doors or opening the refrigerant may be conveyed to the desired storage points by delivering it into one of the compartments and subsequently actuating the rotary member to carry the refrigerant to the point of delivery, together with the person charged with the duty of storing the refrigerant in the respective corners or spaces. After the refrigerant has been delivered the rotary member may again be actuated to bring the attendant or workman back to the door-way.

I claim—

1. A refrigerator, comprising the combination with a main chamber provided with a door-way and door, of a revolving member located within the main chamber and provided with top and bottom walls, partition walls sub-dividing the revolving member 100 into a series of open compartments, interior vestibule walls on opposite sides of the door-way, provided with packing strips adapted for selective registry with the vertical compartment walls, and means for actuating the 105 rotary member from the exterior to bring said walls successively into registry with the packing strips, together with a packing member spanning the space between said vestibule walls at the top of said walls and adapted to bear upon the top of the rotary member, when the door is open, and means for lifting said packing member when the door is closed and supporting it out of frictional contact with the rotary member. 110

2. A refrigerator, comprising the combination with a main chamber provided with a door-way and door, of a revolving member located within the main chamber and provided with top and bottom walls, partition walls sub-dividing the revolving member into a series of open compartments, vestibule walls on opposite sides of the door-way, provided with packing strips adapted for selective registry with the vertical compartment walls, and means for actuating the rotary member from the exterior to bring said walls successively into registry with the packing strips, together with a packing member spanning the space between 120 125 130

5 said vestibule walls at the top of said walls and adapted to bear upon the top of the rotary member, and means connected with the door for lifting said last mentioned packing member when the door is closed, whereby friction of the latter upon the top of the rotary member is avoided when the rotary member is in motion.

10 3. A refrigerator, comprising the combination with a main chamber provided with a door-way and door, of a revolving member located within the main chamber and provided with top and bottom walls, partition walls sub-dividing the revolving member into a series of open compartments, vestibule walls on opposite sides of the door-way, provided with packing strips adapted for selective registry with the

15 vertical compartment walls, means for actuating the rotary member from the exterior to bring said walls successively into registry with the packing strips, said means comprising a shaft journaled under the supporting member, a shaft carried by the door, means for coupling said shafts together in closing position of the door, a wheel on the first named shaft engaging with the revolving member to rotate said member, and means carried by the door for rotating said door carried shaft.

20 25 In testimony whereof I affix my signature in the presence of two witnesses.
